UNITED STATES PATENT OFFICE

131,475

DESIGN FOR A BUTTON OR SIMILAR ARTICLE

Alfred Carl Welchlin and Jennings Bryan
Newcom, Fairmont, Minn.

Application December 16, 1941, Serial No. 104,663

Term of patent 3½ years

To all whom it may concern:

Be it known that we, Alfred Carl Welchlin and Jennings Bryan Newcom, are citizens of the United States residing at Fairmont, in the county of Martin and State of Minnesota, have invented a new, original, and ornamental Design for a Button or Similar Article, of which the following is a specification, reference being had to the accompanying drawing, forming part thereof.

We claim:

The ornamental design for a button or similar article, as shown.

ALFRED CARL WELCHLIN.
JENNINGS BRYAN NEWCOM.
